Primary Examiner — Thomas Johannes*Assistant Examiner* — Catherine Posthauer(74) *Attorney, Agent, or Firm* — Rutan & Tucker, LLP; Hani Z. Sayed**CLAIM**

The ornamental design for an short swirl bell bottle with straight ribs, as shown and described.

DESCRIPTION

FIG. 1 is a bottom, front, left side, perspective view of the present invention;

FIG. 2 is front elevation view;

FIG. 3 is a rear elevation view;

FIG. 4 is a left side elevation view;

FIG. 5 is a right side elevation view;

FIG. 6 is a top plan view; and,

FIG. 7 is a bottom plan view.

1 Claim, 3 Drawing Sheets(56)
